(57) **CLAIM**

The ornamental design for an automatic injector container, substantially as shown and described.

DESCRIPTION

FIG. 1 is a perspective view of an automatic injector container showing our new design;

FIG. 2 is a top plan view showing the cap of the container of FIG. 1;

FIG. 3 is a perspective view of the container of FIG. 1 without a cap; and,

FIG. 4 is a side elevational view of the container of FIG. 3.
